UNITED STATES PATENT OFFICE.

ARAS J. WILLIAMS, OF UTICA, NEW YORK.

LINED GARMENT AND PROCESS OF MAKING THE SAME.

1,298,845.

Specification of Letters Patent.

Patented Apr. 1, 1919.

Application filed June 16, 1917. Serial No. 175,066.

To all whom it may concern:

Be it known that I, ARAS J. WILLIAMS, of Utica, in the county of Oneida and State of New York, have invented certain new and

5 useful Improvements in Lined Garments and Processes of Making the Same; and I do hereby declare that the following is a full, clear, and exact description thereof, which will enable others skilled in the art 10 to which it appertains to make and use the same, reference being had to the accompanying drawings, and to the reference-numerals marked thereon, which form part of this specification.

15 My present invention relates to a new construction of lined garments and particularly to a new form of seam for such garments and the process of making the same.

The purpose of my present invention is to 20 provide a new and improved form of constructing lined garments and particularly the main seams thereof and to provide a new and improved process or method of constructing such garments and the main seams 25 thereof.

A further purpose is to provide a lined garment wherein the edges of corresponding pieces of cloth and of lining are held together by and inclosed within a piece of 30 piping or similar material and wherein the main seams are formed by a row of stitches holding such garment portions together with the face of the cloth of said portions toward 35 each other and with the said row of stitches spaced from the piping so as to leave a projecting strip of cloth and lining upon each portion beyond said seam and upon the inside of the garment, said projecting portions preferably being pressed back flat upon 40 their own portions of the garment.

A further purpose of my invention is to point out a process or method of making a garment having the construction above mentioned.

45 A further purpose of my invention is to provide a garment which is attractive in appearance and workmanlike in construction and which is particularly well adapted to be made conveniently and accurately.

50 A further purpose is to provide a garment of such construction that it may be made without additional labor or with even less labor than heretofore and will present a finished appearance and yet be susceptible 55 of being readily altered in the seams without endangering the fit of the garment and

particularly without disarranging the relative position of the lining and the main cloth.

A further purpose of my invention is to 60 provide and point out methods of making a garment and the seams thereof having the advantages and constructions above mentioned.

Figure 1 shows the inside of a suit coat 65 embodying my invention.

Fig. 2 is a plan view upon an enlarged scale of the inside of a portion of a garment and seam embodying my invention.

Fig. 3 is a sectional view upon line 3—3 70 of Fig. 2.

Fig. 4 is a sectional view through a piece of cloth and a piece of lining having their edges bound together by piping to form a garment portion according to my invention. 75

Fig. 5 is a sectional view through two garment-portions after they have been sewed together but before they have been spread out into the position they occupy in the finished garment. 80

While I have shown my invention in Fig. 1 as applied to an ordinary lined suit coat, it will be understood that my invention is not limited to suit coats, but is applied broadly to lined coats, lined over-coats and 85 other garments.

Referring to the drawings in a more particular description, it will be seen that I have shown in Fig. 1 an ordinary suit coat having several main garment-portions 8, 9, 90 10 and 11 meaning thereby the main portions of the garment which are each to be formed of a proper-shaped piece of the cloth proper or outside fabric 12 or 12^a of the coat and a substantially correspondingly shaped piece 95 of lining 13 or 13^a which portions are to be brought together and fastened to each other near their edges by the main seams of the garment such as at the sides of the garment and down the back of the garment. 100

For the purpose of convenience and definiteness in description I have made Figs. 2—5 by their numerals illustrate the garment-portions 8 and 9 on the main seam uniting said portions, but it will be understood that said Figs. 2—5 illustrate my invention wherever used upon the garment and as used upon any garment. 105

The piece of cloth 12 or 12^a and the piece 110 of lining 13 or 13^a for each garment-portion are brought together with their edges that are to help make the main seams closely in

alinement; then a piece of piping or similar binding material 14 is placed about the edges of said cloth and lining as shown in Fig. 4 with said piping inclosing the raw edges of both cloth and lining and extending a short distance back upon the face or outer surface of the cloth and the face of the lining or that surface which is toward the wearer of the garment. The piping is secured in this position by a row of stitches 15 preferably passing through the cloth, the lining and both layers of piping.

Two garment-portions as 8 and 9 composed respectively of cloth 12, lining 13 and cloth 12^a and lining 13^a, and each separately bound as described by piping 14, are brought together with the face of the cloth of one portion against the face of the cloth of the other portion as indicated in Fig. 5 and then securely and strongly fastened to each other by a row of stitches 16 passing completely through the lining and cloth of both portions, that is through the lining 13 and cloth 12 of portion 8 and the cloth 12^a and lining 13^a of portion 9. Then the seam is spread out by extending the main garment-portions in opposite directions and by extending the edge strip 8^a of garment-portion 8 and the edge strip 9^a of garment-portion 9 likewise in opposite directions and pressing the said seam flat into the position shown in the drawings and particularly shown in cross-section in Fig. 3. The edge strips 8^a and 9^a are the parts that are beyond the main seam 16 or toward the edge of the said garment-portions and toward the piping 14. As when the said sections were joined by said main seam the face of the cloth 12 of garment-portion 8 was toward the face of the cloth 12^a of garment-portion 9, it will be seen that when the seam is spread out and completed as above mentioned the edge strips 8^a and 9^a will be on the inside of the garment, that is toward the wearer, and will furthermore be on the inside of the garment relative to the lining of said garment or in other words between the lining proper and the wearer of the garment. These edge strips will, therefore, be in plain sight when the inside of the garment is looked at as in Figs. 1 and 2 and that is the intention and one of the advantages of my invention. It will be seen furthermore that in the ordinary embodiment of my invention these edge strips will preferably be wider than the portion of the piping upon either side of said edge strips. The completed seam, therefore, viewed from the inside of the garment will show two of these edge strips turned back in opposite directions from the row of stitches 16 and leaving in sight at each side of said row of stitches a section of the face or outer surface of the cloth 12 or 12^a and therebeyond a band of piping 14. Toward that edge of the band of piping in view that is toward the

row of stitches 16 will be the row of stitches 15 that connects the two layers of each piece of piping and the single layer of cloth and the single layer of lining. Beyond these bands of piping on each side of the seam the 70 face of the lining 13 and 13^a will appear.

It will be obvious that the edge strips projecting beyond the main seams and thus turned down may be of any desired extent in width and likewise that the portion of 75 each of said strips to be covered by the piping may be varied as desired. The piping, however, should be of sufficient width so that when folded over the edge of its contained cloth and lining the row of stitches 80 will be far enough back from the edge of the cloth and lining to make a good strong seam. Furthermore it is preferred that the width of said piping be such that, even when folded, the band thereof then appearing, as 85 the inside of the garment is looked at, will be of sufficient width to be noticeable and in keeping with the width of the edge strips 12 or 12^a. It is preferred also that the said edge strips be of such width that between the 90 two bands of piping at each seam there will appear an appreciable width of the face or outer surface of the main cloth or fabric 12 and 12^a. In other words instead of the seam being concealed and unnoticeable it is made 95 so as to be plainly visible and give a pleasing appearance to the inside of the coat in that there will usually be more or less of a contrast between the colors and pattern of the cloth, the lining and the piping or at least 100 of two of them.

It will be seen that a garment constructed as herein described will have its lining secured to the main cloth of the garment at each of the seams constructed in accordance 105 with my invention. In full lined coats as heretofore constructed the lining has not been fastened to the cloth except at the side seams by an additional operation. In fact in many such full lined garments as heretofore made the seams of the lining did not coincide with the seams of the main fabric of the garment.

It will be seen that a garment constructed in accordance with my invention will be very 115 substantial and will tend to maintain its shape permanently. The lining and cloth being fastened to each other along each of the main seams, tend to decidedly strengthen each other, prevent the garment being strained or becoming mis-shaped and prevent pulling out on the seams.

Furthermore my construction is an advantageous one in that the cloth for a given 125 garment-portion and its corresponding piece of lining are separately assembled and secured to each other at one or more of their edges by means of said piping. This operation may be readily performed since the operator has access to the edges of both the 130

cloth and the lining and is free to adjust them into alinement. Another reason for this operation being readily and accurately performed is that the garment-portions may 5 and usually will be assembled separately and during such assembling they may be laid flat upon the table or may be handled more freely by the workman not being impeded by having a whole or large part of a 10 garment to handle. It will be seen that the use of the piping is not simply for ornamentation in the finished garment and not even simply for binding the edges of the projecting strips in the finished garment, 15 but is of great assistance in making up the different sections and joining the different sections into a complete garment. During the making of the sections and the making of the garment by assembling the different 20 sections the piping holds the lining securely in place upon the cloth. This is of special advantage when the edges of two garment-portions are brought together as shown in Fig. 5 to make a main seam of a garment. 25 The piping then insures the lining and cloth of each portion being in proper position for the main seam provides a smoother edge for handling and alining the garment-portions and in general holds each garment-portion 30 as a unit instead of allowing them to be a separate piece of cloth and lining as would otherwise be the case.

It will be seen that the binding of the edges of the garment-portions by said piping 35 permanently secures each piece of lining to its respective piece of cloth so that if the garment has to be altered in the making or as an incident to its being sold or fitted a main seam may be readily undone by cutting the row of stitches 16 as far as needed 40 and the garment let out or brought in from either or both sides without the lining and cloth losing their relative position. In effecting such alterations simply the row of 45 stitches 16 will be cut and new stitches formed where needed without undoing the piping at the edge of either garment-portion unless it is desired to loosen the piping to allow of the projecting strip or strips being varied to harmonize with the alterations 50 made.

What I claim as new and desire to secure by Letters Patent is:

1. As a new article of manufacture, a 55 lined garment having the edges of its corresponding pieces of cloth and lining inclosed within a relatively narrow piping and held

together by rows of stitches through said four thicknesses only, namely said cloth and lining and both thicknesses of piping and 60 relatively close to the edge of the cloth and having the adjacent garment portions composed of said cloth and lining secured to each other solely by a main row of stitches spaced back from the edges of said portions 65 with the strips of said portions beyond said main row of stitches within the garment and turned back in opposite directions, each upon the lining of its own portion but free from the adjacent main portion of lining 70 and cloth, a zone of the face of the cloth being left on the exposed side of each of said turned-back strips between the main row of stitches and its binding of piping.

2. The process of forming seams for lined 75 garments which consists of placing corresponding pieces of cloth and lining together back to back with their edges within a piece of piping, sewing said garment portions together solely by seams back from said bound 80 edges and with the projecting strips on the inside of the garment and spreading out said projecting strips in opposite directions each upon the lining of its own portion but free from its adjacent main portion of lining 85 and cloth or any part of the garment except at said main seam and leaving a zone of the face of the cloth on the exposed side of each of said turned-back strips between the main row of stitches and its binding of 90 piping.

3. The process of forming seams for lined 95 garments which consists of placing corresponding pieces of cloth and lining together back to back with their edges in line, inclosing both edges within a piece of piping by sewing through said four layers only, namely said cloth and lining and both layers of piping relatively close to said edges, sewing said garment portions together solely by main 100 seams back from said bound edges and with the projecting strips on the inside of the garment and spreading out said projecting strips in opposite directions, each upon the lining of its own portion but free from the adjacent main portion of lining and cloth, a 105 zone of the face of the cloth being left on the exposed side of each of said turned-back strips between the main row of stitches and its binding of piping.

In witness whereof I have affixed my signature, this 13th day of June 1917.

ARAS J. WILLIAMS.
